UNITED STATES PATENT OFFICE

CHARLES L. GEHNRICH, OF ELMHURST, NEW YORK, ASSIGNOR TO GEHNRICH OVEN CO., INC., OF LONG ISLAND CITY, NEW YORK, A CORPORATION OF NEW YORK

OVEN SAFETY CONTROL

Application filed September 30, 1929. Serial No. 396,168.

This invention relates to automatic control of oven ventilation and heating. When baking materials which emit combustible vapors, for example, japan articles to which 5 the japan has been applied with the aid of volatile solvents such as benzine, benzol, alcohols etc., the danger exists that the combustible vapors which are first given off will not be completely removed, by reason of which 10 fact, when the oven becomes hotter an explosion will take place. Such explosions are very frequent in this art and have been the source of much trouble and expense.

The principal object of this invention is to 15 eliminate all hazard in baking materials which emit combustible vapors by the provision of positive exhaust at all times when heat is on and maximum exhaust during the period when combustible vapors are given 20 off. As a necessary incident to the perfect fulfillment of this object I provide means for shutting off the heat supply in case anything should happen to prevent the desired speed of exhaust.

25 A further object of my invention is to automatically reduce the exhaust to practical requirements for the conservation of heat after the combustible vapors are removed.

Another object of my invention is to provide 30 means for automatically cutting off all heat supply when the oven door is opened for any reason.

A still further object of my invention is to so arrange the parts of my device that in 35 case the oven door is opened thereby shutting off the heat before the aforesaid maximum exhaust period is ended, said maximum exhaust period will be started anew on the closing of the door. This provision is a safe- 40 guard against those situations where a work- man opens the oven door before the maximum exhaust period is ended in order to put in fresh material to be baked. If only the re- mainder of the maximum exhaust period were 45 to be allowed on the closing of the door, there would not be sufficient time for the combustible vapors from the new material to be removed from the oven and an explosion would result.

50 Further objects and advantages of my in-

vention will appear from the detailed description of the accompanying drawing which is a vertical section through an oven equipped with the aforesaid means. Referring more specifically to said drawings, 1 represents an 55 oven of the usual construction having a door 2 and gas circulating pipe 3 connected to a fan 4 which is operated by an electrical motor, not shown, which is energized by a magnetic starter 5. The oven has the usual 60 screened air-inlet 18 near the base which is a conventional construction common to every oven. There can be as many of these and in such position as desired. Gases are withdrawn from the oven by the fan through the 65 pipe 6 and returned or exhausted through the pipe 7. Between the fan and the pipe 7 is a horizontal pipe 8. It is to be understood, however, that these pipes may be placed in any plane or at any angle to each other without departing from the scope of my invention. 70

Pivoted in the pipe 7 adjacent the junction of the same with the pipe 8 is a damper 9 adapted to connect the pipe 8 with the interior 75 of the oven or with the atmosphere as desired. Or the damper 9 may be so adjusted that part of the effluent gases return to the oven and part go off into the atmosphere. This adjustment is made possible by means of a 80 screw 10 mounted on the pipe 7 and capable of being projected into the path of the damper 9.

On the inner end of the damper 9 is a weight 11 which tends to hold the damper 9 in a position to prevent the return of the 85 effluent gases to the oven and to insure complete exhaust to the outside. Of course it is obvious that this weight can be placed on the outer end of the damper to normally hold said damper in closed position. At the outer end 90 of the damper 9 is mounted a solenoid 12 which is energized from a source of power 13. In the solenoid circuit is a time interval relay 14 of the conventional motor type having an auxiliary contact which can be adjusted 95 to close or open the solenoid circuit after any desired interval of time. In the embodiment shown, the time relay switch closes the solenoid circuit after a predetermined period. In the event, however, that the weight is placed 100

on the outer end of the damper the time relay switch used is one which opens the solenoid circuit after a predetermined interval. Connected in series with the solenoid circuit is a switch 15, one contact of which is on the oven wall and the other contact of which is on the oven door whereby when the oven door is opened there is a break in the solenoid circuit.

10 Also mounted in pipe 7 is a hand operated damper 16 for controlling the recirculation of the effluent gases. Frequently, for one reason or another, the fan 4 fails to function properly whereby the combustion vapors are not removed from the oven. In such a case if heat were applied to the oven continuously an explosion would take place. In order to safeguard against such a possibility a safety switch 17 is inserted in the pipe 8. The switch 15 consists of a vane suspended in said pipe and adapted to be swung into circuit-closing position by the draft in said pipe. This switch is in series with the heating circuit whereby when, for any reason, the draft in pipe 8 ceases, the vane assumes an upright position and breaks the heating circuit.

The operation of my device is very simple. When the oven door is closed, thereby starting the fan motor and subsequently closing the heating circuit, the damper 9 is held by weight 11 in a position to force all the effluent gases into the atmosphere. The time relay switch 14 is set so as to close after an interval predetermined to be sufficient to rid the oven of combustible gases. After this interval has elapsed switch 14 closes, thereby energizing the solenoid 12 which moves damper 9 to a position regulated by the screw 10. This position is mainly determined by the ventilation desired in the oven and is usually such that, while the material to be baked is being dried, the effluent gases are completely removed from the oven while they contain vapor in explosive proportions. It is to be understood that if weight 11 be placed on the outer end of the damper the action is reversed. That is, the solenoid circuit is closed upon the closing of the oven door and the energized solenoid holds the damper open by overcoming the force of weight 11. The time relay, being of the type which opens after a predetermined interval, breaks the solenoid circuit after said interval whereby said damper is closed to the desired position by weight 11. The rate of exhaust can be regulated by totally closing the hand damper 16 and adjusting the damper 9 so as to permit any desired quantity of gas to escape. As before stated, if for any reason the fan should fail to function, the safety switch 17 will cut off the supply of heat. Likewise, if the oven door should open for any reason, the heating supply would be cut off. It is to be understood that there is no electrical connection between the heating circuit and the oven door

circuit. The breaking of the latter merely breaks the former by reason of the fact that the breaking of the latter breaks the fan circuit whereby switch 17 is opened. The opening of the switch 17, of course, breaks the heating circuit.

Having thus described the nature and objects of my invention and illustrated a preferred embodiment of the same, which embodiment, however, is to be taken as illustrative rather than limitative, what I claim as new and desire to secure by Letters Patent is:

1. In an oven for baking materials giving off combustible gases, in combination, an outlet pipe for withdrawing gases from said oven, an inlet pipe connected with said outlet pipe for returning said gases to said oven, a damper for alternately connecting said outlet pipe with the atmosphere and with said inlet pipe, and means for causing said damper to connect said outlet pipe completely with the atmosphere for a predetermined period at the beginning of the bake.

2. In an oven for baking materials giving off combustible gases, in combination, an outlet pipe for withdrawing gases from said oven, an inlet pipe connected with said outlet pipe for returning said gases to said oven, a damper for alternately connecting said outlet pipe with the atmosphere and with said inlet pipe, means for causing said damper to connect said outlet pipe completely with the atmosphere for a predetermined period at the beginning of the bake, and means for automatically moving said damper at the end of said predetermined period.

3. In an oven for baking materials giving off combustible gases, in combination, an outlet pipe for withdrawing gases from said oven, an inlet pipe connected with said outlet pipe for returning said gases to said oven, a damper for alternately connecting said outlet pipe with the atmosphere and with said inlet pipe, means for causing said damper to connect said outlet pipe completely with the atmosphere for a predetermined period at the beginning of the bake, means for automatically moving said damper at the end of said predetermined period, and means for regulating the movement of said damper.

4. In an oven for baking materials giving off combustible gases, in combination, an outlet pipe for withdrawing gases from said oven, an inlet pipe connected with said outlet pipe for returning said gases to said oven, a solenoid damper for alternately connecting said outlet pipe with the atmosphere and with said inlet pipe, and a weight acting on said damper in opposition to said solenoid.

5. In an oven for baking materials giving off combustible gases, in combination, an outlet pipe for withdrawing gases from said oven, an inlet pipe connected with said outlet pipe for returning said gases to said oven, a

- source of power, a solenoid damper for alternately connecting said outlet pipe with the atmosphere and with said inlet pipe, a weight for causing said damper to connect said outlet pipe completely with the atmosphere for a predetermined period at the beginning of the bake, and a time relay switch for connecting said solenoid to said source of power at the end of said predetermined period whereby said solenoid is energized and moves said damper. 5 of the outlet pipe therewith having a portion extending outside said inlet pipe, means on its inner end to normally close said junction, and electrical means on said extended portion for automatically opening said junction 70 after a predetermined period.
6. In an oven for baking materials giving off combustible gases, in combination, an outlet pipe for withdrawing gases from said oven, an inlet pipe connected with said outlet pipe for returning said gases to said oven, a source of power, a solenoid damper for alternately connecting said outlet pipe with the atmosphere and with said inlet pipe, a weight 10 for causing said damper to connect said outlet pipe completely with the atmosphere for a predetermined period at the beginning of the bake, a time relay switch for connecting said solenoid to said source of power at the 15 end of said predetermined period whereby said solenoid is energized and moves said damper, and means for regulating the distance moved by said damper. 20
7. In an oven for baking materials giving off combustible gases, in combination, an outlet pipe for withdrawing gases from said oven, an inlet pipe connected with said outlet pipe for returning said gases to said oven, a source of power, a solenoid damper for alternately connecting said outlet pipe with the atmosphere and with said inlet pipe, a weight 25 for causing said damper to connect said outlet pipe completely with the atmosphere for a predetermined period at the beginning of the bake, a time relay switch for connecting said solenoid to said source of power at the 30 end of said predetermined period whereby said solenoid is energized and moves said damper, and means for regulating the distance moved by said damper. 35
8. In an oven having an outlet pipe for withdrawing gases therefrom and an inlet pipe connected with said outlet pipe for returning said gases to said oven, a damper pivoted in said inlet pipe opposite the junction 40 of the outlet pipe therewith having a portion extending outside said inlet pipe, means on its inner end to normally close said junction, and means on said extended portion for automatically opening said junction after a predetermined period. 45
9. In an oven having an outlet pipe for withdrawing gases therefrom and an inlet pipe connected with said outlet pipe for returning said gases to said oven, a damper pivoted in said inlet pipe opposite the junction 50 of the outlet pipe therewith having a portion extending outside said inlet pipe, means on its inner end to normally close said junction, and electrical means on said extended portion for automatically opening said junction 55 after a predetermined period. 55
10. In an oven having an outlet pipe for withdrawing gases therefrom and an inlet pipe connected with said outlet pipe for returning said gases to said oven, a damper pivoted in said inlet pipe opposite the junction of the outlet pipe therewith having a portion extending outside said inlet pipe, a weight on its inner end to normally close said junction, and electrical means on said 60 extended portion for automatically opening said junction after a predetermined period. 65
11. In an oven having an outlet pipe for withdrawing gases therefrom and an inlet pipe connected with said outlet pipe for returning said gases to said oven, a damper pivoted in said inlet pipe opposite the junction of the outlet pipe therewith having a portion extending outside said inlet pipe, a weight on its inner end to normally close said 70 junction, and a solenoid on said extended portion for automatically opening said junction after a predetermined period. 75
